UNITED STATES PATENT OFFICE.

HARRIETTE ENSLEY HODGSON, OF NEW YORK, N. Y.

RAILWAY GATE.

Application filed March 15, 1924. Serial No. 699,545.

To all whom it may concern:

Be it known that I, HARRIETTE ENSLEY HODGSON, a citizen of the United States, and a resident of New York city, in the 5 county and State of New York, have invented a new and useful Railway Gate, of which the following is a specification.

My invention relates to railway gates for protecting road crossings, and the object is 10 to provide a very strong reliable gate, not likely to get out of order, capable of yielding readily to pressure from the inside while presenting a complete barrier against forces 15 exerted from the outside. A further object is to enable the gate to be operated quickly and easily without reliance upon mechanism subject to derangement. Still another object is to provide a horizontally 20 swinging gate which tends of itself to stay closed, together with means for supporting the free end or ends of the gate in the closed position, which means preferably also exerts a restraining influence, not however 25 of a positive character, against accidental opening. The invention further provides both, or either, positive and non-positive means for holding the gate open, as well as a support for the gate in the open position, which support preferably constitutes 30 a means for holding the gate open. The invention further provides a strong foundation and bracing structure for the gate. Other objects and features will become apparent as the specification proceeds.

In the accompanying drawings, forming a part hereof:

Fig. 1 is a plan view of a double gate embodying the invention;

Fig. 2 is a front elevation looking at the same gate from the outer side, that is to say from the roadway;

Fig. 3 is a plan view on a smaller scale showing a railroad crossing with gates at opposite sides;

Fig. 4 is a side elevation, showing the gate open;

Fig. 5 is a front elevation of a single gate;

Fig. 6 is an enlarged detail front elevation of the adjoining lower portions of a 50 double gate, with portions of the fixed structure in section;

Fig. 7 is an enlarged detail side elevation looking at the side of the part of the central post seen in Fig. 6, portions of the

fixed structure being broken away and in 55 section;

Fig. 8 is a sectional edge elevation of a portion of one of the side frames, showing the lower portion of one of the gates supported in the open position; 60

Fig. 9 is a horizontal section through the center part of a modified construction, showing the adjoining portions of the two gates in plan, one closed and the other partly open; and 65

Fig. 10 is a front elevation of the lower part of the post of this modification, the gates being indicated by dotted lines.

Figs. 1 to 4 and 6 to illustrate a double gate construction will first be described. 70

There are two strong hinge posts 2 at opposite sides of the roadway, and a strong center post 3 in the middle of the roadway. These posts are planted on firm foundations 4, of concrete, concrete and metal, metal 75 or wood, sunk in the ground. The hinge posts are braced longitudinally of the roadway above ground by side frames extending in both directions therefrom and preferably comprising inclined members 5, 6, the members 6 of which, at the outer side, away from the tracks, are longer and extend further than the members 5 at the inner side. The center post is likewise braced by inclined members 7, 8 extending in both directions centrally of the roadway, these members being firmly bolted or riveted to the post as indicated at 9. The members 5, 6 and 7, 8 are secured at their outer, lower ends to other blocks or piles 41, and the 80 several posts; their inclined brace members, and the foundation blocks are advantageously interconnected and braced at or below the level of the roadway by a system of intersecting bars 10, forming a grille, at the 85 intersections of which may be additional foundations 42. This affords a very complete system of ground framing, which may, however, be reduced or simplified to such extent as may be deemed expedient. 90

The inclined brace members 7, 8 for the center post serve the additional purpose of guards for the post, to deflect the wheels of vehicles that might otherwise strike the post. 100

On the top of the center post is a light 11. This is preferably an electric light, but where electricity is not available provision

will be made for mounting an oil lantern on the post. Lights could also be placed upon the side posts, but it is particularly desirable to illuminate the center post, both to keep 5 automobilists from running into it and to furnish a warning signal showing the presence of a crossing. The light should be red, or of some other appropriate color or marking.

10 Two strongly-framed gate members 12, of metal construction preferably, are hinged to the side posts 2. The hinges, which are marked 13, are at the faces of these posts away from the tracks, and are disposed at a 15 slight inclination to the vertical, the inclination from below upwardly being toward the roadway, and the gates hang at a moderate downward and inward inclination, so that they tend by gravity to remain closed with 20 their free ends against the outer face of the center post.

Fixed to or formed on the outer side of the center post, toward the bottom, is a step-support or ledge 14 (Fig. 7). This support 25 is preferably made of an iron bolted to the post, and with advantage may be bent from the upper end of the inclined brace 8. This step support is placed at such height that the bottoms of the gates, at their adjoining ends, 30 will rest frictionally and with substantial weight upon the step when the gates are closed. For this purpose the flat platform surface 15 of the step is a little above the height at which the gates would hang naturally, so that it is necessary for the gates 35 in closing to ride slightly up on the terminal incline 16 of the step. The slight play that naturally exists in the hinges or slight give in the gates themselves allows for this, and 40 when the ends of the gates are thus caused to stand frictionally on the support, the gates will resist accidental opening, while being capable of being pushed off from the inside either by a vehicle or by the watchman.

45 Pressure from the opposite direction however is taken solidly by the posts, the outer faces of which are overlapped by the gates. In order to increase the effect of the non-positive, frictional holding of the gates in 50 closed position the platform surface 15 may with advantage be inclined slightly downward from a high point 17 toward the post, so that the gate has to rise slightly in order to be pushed off the support. The lower 55 corners 18 of the gates which cooperate with the step are cut at such angle to the general inclination of the gates in the closed position as to be substantially horizontal.

Similar step supports 19 (Fig. 8) are secured to the side frame members 6 to support and hold the gates in the open position. These steps have inclined ride-up lips 20, a platform support 21, and a high point 22, which may be more pronounced than in the 65 case of the step 14, so as to require the at-

tendant to exert a moderate lifting effort on the gates before they can be freed from the steps.

The gates are also preferably provided at their outer sides with hooks 23 adapted to engage with suitable eyes 24 on the side-frames 6. These fastenings may be used for extra security in keeping the gates open, but time can be saved if the steps 19 alone are relied upon. It is desirable to make the positions of the hooks noticeable by prominently marking the spots 25 on the gates where they are placed, for example a white spot on a red or otherwise colored gate, so that the fastenings can be readily found at night.

Handles 26 are provided on the inner sides of the gates for convenience in closing them.

The modification illustrated in Figs. 9 and 10 relates to the center post and its step support. The post is marked 3^a. In this 85 form the ends of the gate, instead of overlapping the body of the post, laterally abut extension wings 30 formed on or secured to opposite sides of the body. These stop wings may be in the form of angle-irons as 90 shown bolted through the post at 31. The step support is divided in two, its two parts 14^a being also at opposite sides of the post. These steps may be formed or attached in various ways, and can advantageously be 95 formed in one piece with or secured to the lower ends of the wings 30. In essential construction and principle of operation the divided step is like the single step on the outer face of the post, which has been described.

Fig. 5 illustrates a single gate embodying features similar to those of the double gate. While the double gate is preferred for general purposes, the single gate may be used 105 with advantage in some cases, as on narrow roads.

The hinge post 2^b is located at one side of the roadway, and the abutment post 3^b at the opposite side. The gate is swung at an 110 inclination as in the other construction and cooperates with a step support 14^b on the post 3^b, while another step support 19^b serves to hold the gate open. Lights 11^b are shown upon both posts.

What I claim as new is:

1. A railway gate comprising a hinge post, an abutment post, a gate swung at an inclination from said hinge post and having its lower free corner formed substantially horizontal, and a step support on the abutment post to cooperate with such corner portion of the gate, substantially as described.

2. In a railway gate, hinge posts at opposite sides of the roadway, a central abutment post, laterally swinging gates hung on the hinge posts, and combined brace and guard members for the center post, substantially as described.

HARRIETTE ENSLEY HODGSON.
